United States Patent

Des. 242,502
Patented Nov. 23, 1976

242,502

SIGN

John E. Hubitsky, 112 St. Philip Court,
Danville, Calif. 94526

Filed Nov. 10, 1975, Ser. No. 630,281

Term of patent 14 years

Int. Cl. D20—03

U.S. Cl. D96—12 R

FIG. 1.

FIG. 3.

FIG. 2.

FIG. 4.

FIG. 6.

FIG. 5.

FIG. 1 is a front and right side perspective view of a first embodiment of a sign showing my new design;

FIG. 2 is a top plan view of the first embodiment shown in FIG. 1;

FIG. 3 is an elevational view taken on the plane designated by line 3—3 in FIG. 2;

FIG. 4 is a front and right side perspective view of a second embodiment of a sign showing my new design;

FIG. 5 is a top plan view of the embodiment illustrated in FIG. 4; and

FIG. 6 is an elevational view taken on the plane designated by line 6—6 in FIG. 5.

The rear of the sign of FIG. 4 bears indicia corresponding to the indicia shown in FIG. 6. The shaded areas of the sign are red and the nonshaded areas are white.

I claim:

The ornamental design for a sign, as shown and described.
